UNITED STATES PATENT OFFICE.

ALEXANDER CSIGA, OF CAMILLUS, NEW YORK.

VACUUM ICE CHEST.

Application filed July 23, 1924. Serial No. 727,746.

This invention relates to vacuum ice chests and it consists in the novel features herein-after described and claimed.

An object of the invention is to provide an ice chest structure having a lining structure in which a vacuum may be established for the purpose of isolating the interior compartment of the chest from the external atmosphere in order that the ice which is contained within the chest may be retained in a congealed condition and that the contents of the chest may be kept properly refrigerated for an indefinite period of time.

With this object in view the chest comprises an outer casing, preferably of wood and which is lined with two thicknesses of sheet metal to render the wall of the casing air tight and to prevent the said sheets from warping inwardly when the vacuum is established within the chest. A compartment is located within the casing of the chest and is spaced from the said lining sheet. Strips are interposed between the sheets and the compartments and serve to hold the said parts in spaced relation with respect to each other. The casing is provided with suitable door openings and hinged doors are arranged to close over the said openings, the said doors at their inner sides being provided with linings substantially the same as the lining which is provided at the interior of the body of the casing. An ice pan is supported within the compartment and is provided with a drain pipe made up of slip joint sections and which communicate with a goose neck pipe which is mounted at the bottom of the casing and which passes transversely through the said bottom wall. A lock of especial design and construction is provided and used in conjunction with the side door of the ice chest and may be manipulated to securely hold the said door in a closed position and whereby an air tight joint is provided between the edges of the door and the side walls of the door opening in the casing.

In the accompanying drawings:

Figure 1 is a vertical transverse sectional view of the ice chest.

Figure 2 is a horizontal sectional view thereof cut on the line 2-2 of Figure 1.

Figure 3 is a fragmentary detailed view of the lining of the chest with parts thereof broken away.

Figure 4 is a detail sectional view of a

valve which is used upon the lining of the ice chest.

Figure 5 is a side elevation of a lock which is used upon the ice chest.

Figure 6 is an edge elevation of the lock. 60

The ice chest comprises a casing 1, preferably of wood, having two sheets of metal arranged side by side and lining the inner surface of the casing 1 so as to make the same air tight. A compartment chamber 3 65 is located interiorly of the chest 1 and spaced from the inner sheet 2. Strips 4 are arranged between the inner sheet 2 and the exterior surface of the compartment chamber 3 and serve to hold the said chamber 70 spaced with relation to the said sheet. A valve 5 passes through the wall of the chamber 3 and communicates with the space between the said chamber and the inner sheet 2. The valve comprises a casing 6 having an interiorly located seat 7, a valve 8 movably mounted in the casing and provided with a stem 9 which passes longitudinally through said casing. A spider 10 is inserted in the end portion of the casing 6 75 and serves as a guide for the stem 9. The outer end of the casing 6 is normally closed by a cap 11 and the flexible washer 12 is interposed between the end of the casing and the cap and serves as means for packing 80 or closing the joint between the cap and the casing. The front or side door 13 of the chest is provided at its inner side with a lining similar to that above described, and a valve 5 of the structural arrangement as 85 hereinbefore described. The top door 14 of the chest is provided at its inner side with a lining similar to that hereinbefore described and is also provided with a valve 5.

An ice pan 15 is supported within the compartment chamber 3 upon brackets 16 and is provided with a drain pipe section 17. The said section 17 slips into the upper end of a section 18 and the section 18 slips into the upper end of a section 19 which 100 in turn slips into one end of a goose neck 20 mounted upon the bottom of the compartment chamber 3 and held at a fixed position by a post of solder 21. The other end of the goose neck 20 connects with a drain pipe 22 which passes through the bottom of the casing 1. The casing 1 is provided at its front side with a hinged apron 23 and is adapted to swing down over the drip pan (not shown) and which is placed under the 110

casing below the drain pipe 22 in the usual manner.

By applying a suction pump to the valves 5 the air may be exhausted from the spaces between the lining sheet 2 and the walls of the compartment chamber and thus the vacuum is established around the compartment chamber. The strips 4 prevent the sheets from buckling inward when the air 10 is exhausted from the space between the sheets and the walls of the compartment chamber and the two sheets arranged side by side make an air tight wall which prevents air from the exterior entering the 15 space between the lining sheet and the walls of the compartment chamber.

A lock casing 24 is mounted upon the exterior surface of the front door 13 and a bolt 25 is slidably mounted in the said casing. The said bolt is provided at its upper side with notches 26 which may receive the intermediate portion of a spring 27 located within the casing and whereby the said bolts may be held at a projected or retracted position with relation to the casing. The casing 24 is provided with a key-hole opening 28 through which a key may be inserted and engaged with lugs 29 mounted at the lower side of the bolt 25 and 25 which may be used for moving the said bolts. A handle 29 is provided at one end with a disc 30 which is pivotally mounted at the side edge of the lock casing 24. The disk 30 is provided with a recess 31 which 30 may receive the end of the bolt 25 when the said bolt is projected with relation to the casing 24 and whereby the handle 29 is held against turning movement with re-

lation to the lock casing. A keeper plate 32 is mounted upon the casing of the ice 40 chest and is provided with a lug 33 which is inwardly disposed. The disk 30 is provided with a cam flange 34 which may be moved under the lug 33 and whereby the door 13 may be secured at a closed position 45 with relation to the door opening in the casing 1.

Having thus described my invention, what I claim is:—

1. An ice chest comprising a casing, a 50 pair of juxta-posed lining sheets applied to the inner surface of the casing, a compartment chamber located interiorly of said casing and spaced from the lining sheets, and undulated strips interposed between the lining sheet and the wall of the compartment chamber, the width of each strip being disposed rectangularly to the walls of the compartment chamber and the lining sheets. 55

2. An ice chest comprising a casing, a 60 pair of juxta-posed lining sheets applied to the inner surface of the casing, a compartment chamber located interiorly of said casing and spaced from the lining sheets, and undulated strips interposed between the lining sheet and the wall of the compartment chamber, the width of each strip being disposed rectangularly to the walls of the compartment chamber and the lining sheets, and a plurality of valves communicating with 65 the space between the lining sheet and the walls of the compartment chamber. 70

In testimony whereof I affix my signature.

ALEXANDER CSIGA.
